UNITED STATES PATENT OFFICE.

OSCAR ROBERT GRÖNKWIST, OF DAYTON, OHIO.

LUBRICATING SYSTEM AND PUMP THEREFOR.

1,237,029.

Specification of Letters Patent. Patented Aug. 14, 1917.

Application filed April 24, 1913. Serial No. 763,369.

To all whom it may concern:

Be it known that I, OSCAR ROBERT GRÖNKWIST, a subject of the King of Sweden, residing at Dayton, in the county of Montgomery and State of Ohio, have invented certain new and useful Improvements in Lubricating Systems and Controlling and Distributing Pumps Therefor, of which the following is a specification.

10 This invention relates to an improvement in lubricating systems for engines and more especially internal combustion engines and to a pump for use in connection therewith.

One of the primary objects of the present 15 invention is the provision of an improved lubricating system of this character of such a construction as to insure just the proper amount of lubricant being delivered to the various points to be lubricated so as to obviate the many objections due either to over-lubrication or to not enough lubrication.

Another object of the present invention is the provision of an improved system in which the lubricant will be supplied continuously and under pressure to the various 25 points to be lubricated.

A further object of the present invention is the provision of an improved lubricating system in which the various points to be lubricated are arranged in groups, the points of each group being connected serially with a single outlet connection from the pump, thus insuring the delivery of a predetermined amount of oil to each point and 35 also enabling a minimum number of oil delivery pipes to be utilized.

A further object of the present invention is the provision of a lubricating system in which a plurality of bearings are adapted 40 to be lubricated from a single connection leading from a main oil forcing member and in which auxiliary oil forcing means are utilized to insure the passage of the oil to all of the bearings under the proper pressure.

45 A further object of the present invention is the provision of an improved pump for use in connection with a lubricating system which is designed to be positioned independently of the lubricant supply tank and is a small compact structure, so that when

the system is used in connection with automobiles and the like, the pump may be positioned on the dash or at any other point where it will be readily accessible to the 55 operator.

A further object of the invention is the provision of a compact pump of this character which is automatic in its operation and is of such a construction that it will generate sufficient pressure to force the oil through the outlet connections under all conditions, even if any of such connections become slightly clogged.

A further object of the present invention 65 is the provision of a simple compact pump of this character comprising broadly a casing adapted to be connected to a source of lubricant and provided with a plurality of outlet connections, a rotary controlling and 70 distributing member in said casing for controlling the admission of lubricant into the casing through the inlet connection and the discharge of the lubricant from the casing through the outlet connections, in combination with a displacement member which is automatically operable by the rotary controlling and distributing member and which serves to suck the oil into the casing and 75 force the same out therefrom.

80 Other objects of the invention will be apparent from the detail description hereinafter when read in connection with the accompanying drawings forming a part hereof wherein a convenient embodiment of the 85 invention is illustrated, and wherein like characters of reference refer to similar parts in the several views.

Referring now more particularly to the 90 drawings,

Figure 1 is a diagrammatic view of the improved system, the pump being shown in rear elevation, a horizontal section of the crank case of the engine and the parts contained therein being illustrated.

95 Fig. 2 is a side elevation of the engine shaft, one of the engine cylinders and pistons being shown in section.

Fig. 3 is a cross section on line 3—3 of Fig. 2, the piston pin being shown in elevation.

Fig. 4 is an enlarged view of one of the

engine crank pins and pitmen, the pitmen being illustrated in section.

Fig. 5 is a detail view further illustrating the crank pin bearing.

5 Fig. 6 is a rear elevation of the pump.

Fig. 7 is a cross section on line 7—7 of Fig. 6.

Fig. 8 is a front elevation of the pump.

Fig. 9 is a section on line 9—9 of Fig. 7.

10 Fig. 10 is a rear face view of the pump casing and rotary distributing element.

Fig. 11 is a face view of the rear plate of the pump with which all of the outlet pipes make connection.

15 Fig. 12 is an elevation of a plate which is interposed between the rear face of the distributing member of the pump and the face of the member illustrated in Fig. 11.

Fig. 13 is a side elevation of the rotary controlling and distributing element of the pump.

20 Fig. 14 is a cross section through the front portion of the casing of the pump, the front surface of the rotary controlling 25 and distributing element being shown in elevation, and

Fig. 15 is a detail view showing the means carried by one of the engine cranks which is utilized for transferring lubricant from the 30 engine shaft bearing to the crank pin bearing.

In the construction shown in the accompanying drawings, the system is illustrated in connection with an internal combustion 35 engine of the four cylinder type, although it will be obvious that it may be used with engines having any number of cylinders.

Referring now more particularly to the construction shown in the drawings, A 40 designates the crank case of an internal combustion engine, in which is journaled the engine shaft B and the cam shaft C, such shafts being connected by the usual timing gears D which are housed within a timing 45 gear casing D' which is conveniently formed as a part of the engine crank casing. In the embodiment of the invention illustrated, the engine shaft is provided with five bearings E, E', E², E³, and E⁴. The engine shaft is 50 also provided with four cranks F, each of which is adapted to be connected by a suitable pitman G with a piston H which works within a cylinder H'. For convenience of illustration, but one piston and cylinder are 55 shown in the drawings, although it will be understood that the construction of the three other pistons and cylinders is the same as the one illustrated.

The portions of the engine shaft B which 60 are positioned in the engine shaft bearings are each provided with suitable grooves therein enabling a lubricant to pass through the bearing and suitably lubricate the same. In the embodiment of the invention illus-

trated, that portion of the engine shaft 65 which is positioned in each of said bearings is provided with annular grooves b in the exterior thereof adjacent the ends of the bearings and with a diagonal connection groove b' which is disposed upon the exterior 70 of the shaft, lubricant being fed under pressure, in a manner to be hereinafter more particularly set forth, to the bearing so that it will enter one of said grooves and pass to the other of said grooves, thus thoroughly 75 lubricating the bearing. Each of the two end shaft bearings is provided with means for transferring the lubricant which has been passed therethrough to one of the crank 80 pin bearings, such means comprising a dished ring I which is secured to one of the cranks adjacent the bearing and encircling said bearing, which ring is adapted to rotate with the crank and is disposed concentrically to the axis of the engine shaft. The 85 bearing is provided with a short tube i which communicates with the interior of the bearing and receives lubricant from one of the hollow grooves therein, the lower end of 90 said tube being positioned to discharge into said hollow ring. The upper portion of the hollow ring I is provided with a port i' 95 therein which communicates with a passage f which is drilled into one end of the crank pin and from the inner end of which extends a radially disposed port f', which port is 100 adapted upon the rotation of the crank and the rotation of the pitman sleeve around the crank pin to be moved into and out of communication with a semi-circular groove f² 105 which is formed in the lower portion of the pitman sleeve. Means is provided for drawing oil into each of the crank pin bearings, forcing the same therethrough and out therefrom to the piston pin bearing, and 110 from thence into the cylinder. In the particular embodiment of the invention illustrated, each of the crank pins is provided intermediate the ends thereof with an annular groove or channel f³ from which extend two diagonal grooves f⁴ and f⁵, the former of which is adapted to be moved 115 into and out of communication upon rotation of the engine shaft with the groove f² in the pitman sleeve, and the latter of which communicates with a groove f⁶ which 120 partially encircles the crank pin and is adapted upon rotation of the engine shaft to be moved into and out of communication with the lower end of a pipe f⁷ which is 125 tapped into the upper portion of the pitman sleeve which surrounds the crank pin, the upper end of said pipe projecting through the sleeve at the top of the pitman so as to supply lubricant to the bearing between said sleeve and the piston pin H². Secured in the lower portion of the sleeve of the pitman which encircles the crank pin is a ra-

dially disposed sleeve F' in which is loosely mounted so as to be freely movable, a plunger F^2 which projects into the annular groove f^3 , which is formed in the central portion of the crank pin. Inward movement of the plunger F^2 is limited by means of a shoulder which is formed on said plunger and which cooperates with a shoulder formed in the sleeve F' , while outward movement of the plunger is limited by means of an adjustable plug which is secured in the outer end of the sleeve F' . By adjusting the plug the range of movement of the plunger can be so varied that the distance which the plunger moves out of the groove f^3 can be regulated at will, so that the amount of oil which will be displaced at each inward movement of the plunger can be regulated to suit the engine conditions.

20 The piston pin H^2 is provided with suitable grooves into which the oil passes from the pipe f^7 enabling the lubricant to be forced through the piston pin bearing and efficiently lubricate the same and said piston pin and the pin are provided with ports leading to the exterior of the piston, so that the lubricant will be forced after passing through the piston pin bearing into a groove h formed in the side of the piston below the 25 packing rings thereof from whence it will pass onto the wall of the cylinder. The particular construction of grooves in the piston pin forms no specific part of the present invention, but is covered in a separate application, and hence it is believed to be unnecessary to describe the same in detail herein.

The central bearing E^2 of the engine shaft is provided with a pipe e leading therefrom, 40 which pipe communicates with one of the annular grooves b of the portion of the shaft in said bearing, the outer end of said pipe leading to one end of one of the end bearings of the cam shaft C . Leading from the other end 45 of said cam shaft bearing is a pipe c which communicates with one end of the intermediate bearing of the cam shaft C , and leading from the other end of the intermediate bearing of the cam shaft C to one end of the 50 other end bearing of the cam shaft is a pipe c' . It will thus be seen that any lubricant which is forced through the central bearing E^2 will be also forced through all three bearings of the cam shaft C . Those portions of 55 the cam shaft which are journaled within the bearings therefor are conveniently provided with grooves or channels to facilitate the lubrication of said bearings and the passage of the oil therethrough, the construction 60 in the present case being the same as that heretofore described in connection with the engine shaft bearings. The pump which is used in connection with the present system is in the form of a small compact device, so

that the same can be, when the system is 65 used in connection with automobiles, readily secured to the automobile dash or at any other point where it will be easily accessible to the driver, and such pump comprises a cylindrical casing K , which in the present 70 instance is illustrated as being fitted into the dash board of an automobile, the front of said casing being closed and provided with a sight feed k which may be of any suitable type. Closely fitting the interior of the cylindrical casing K is a cylinder K' , which cylinder constitutes a lubricant controlling and distributing member, as will be herein-after more particularly set forth, said member being adapted to be rotated through the 75 medium of a shaft K^2 , which is rigidly secured thereto and projects rearwardly therefrom, which shaft is adapted to be automatically driven in any suitable manner from the engine shaft so as to effect the automatic distribution of the lubricant. In the present instance, I have shown the shaft as provided with a sprocket wheel K^3 which may be driven in any suitable manner from the engine shaft. The shaft is also provided with a hand nut K^4 , so that the oil controlling and distributing member may be rotated manually when the engine is not running, should it be found desirable to do so. The rear end of the casing K is closed by two 80 superposed plates or members L and M which are rigidly secured in position in any suitable manner. The adjacent faces of the plate L and the rotary lubricant controlling and distributing member K' are finished 85 so as to obtain as near as possible a perfect contact with each other and the lubricant controlling and distributing member K' is held up against the face of the plate L by means of a spring washer or other yieldable means k' , which is interposed between the adjacent faces of the plate M and a suitable abutment secured on the shaft K^2 . The form of the rotary distributing and controlling member is such 90 that when the same is snugly held against the face of the plate L , there is provided a space or pocket between the front surface thereof and the front wall of the casing, 95 which space or pocket constitutes a lubricant receiving chamber.

In the embodiment of the invention illustrated in the accompanying drawings, the plate M has tapped thereinto six outlet tubes N , N' , N^2 , N^3 , N^4 and N^5 , the outlet tube N leading to the bearing E^2 of the engine shaft; the outlet tube N' leading to the bearing E' of the engine shaft; the outlet tube N^2 leading to the engine shaft bearing E ; the outlet tube N^3 leading to the engine shaft bearing E^3 ; the outlet tube N^4 leading to the engine shaft bearing E^4 ; and the outlet tube N^5 leading into the timing gear cas-

ing D'. As will be hereinafter pointed out, the construction is such that lubricant is forced under pressure through outlet tubes N, N', N², N³, and N⁴. The lubricant which 5 passes from the tube N⁵ into the timing gear casing will not be under pressure, however, as before entering such tube the lubricant, as will be hereinafter more particularly set forth, passes through a sight feed, and consequently thereafter flows by gravity only. Tapped into the plate member M is also a lubricant inlet tube N⁶ which extends from any suitable lubricant tank O which may be positioned at any desired point. Formed 10 in the face of the plate or member M adjacent the member L are a plurality of grooves, the inner ends of which constitute ports which are disposed in a circular path around the shaft K². There is provided one 15 of such grooves for each of the outlet pipes and for the inlet pipe heretofore referred to; a groove n, the outer end of which communicates directly with the outlet port N; a groove n', the outer end of which communicates directly with the outlet pipe N'; 20 a groove n², the outer end of which communicates directly with the outlet tube N²; a groove n³, the outer end of which communicates directly with the outlet pipe N³; 25 a groove n⁴, the outer end of which communicates directly with the outlet pipe N⁴; a groove n⁵, the outer end of which is connected by ports n⁷ and n⁸ formed in the body of the casing K with the upper end of 30 the sight feed k, the lower end of said sight feed being connected by a port n⁹ formed in the body of the casing with the outlet tube N⁵; and a groove n⁶, the outer end of which is connected to the tube N⁶ which leads from 35 the source of lubricant. The port at the inner end of the groove n⁶ communicates with a circular groove or channel P which is formed with projecting portions, the ends of which are fashioned to constitute ports 40 p which are positioned in the same circular path as the ports at the inner ends of the grooves heretofore described which connect with the outlet tubes. The number of ports p employed corresponds to the number 45 of outlet tubes which are used, there being in the present instance six of such ports. These ports are disposed intermediate the ports which are formed at the inner ends 50 of the channels which connect with the outlet pipes. As the ports p all communicate with a single annular groove or channel and as one of said ports communicates with the oil inlet pipe, it will be seen that all of said ports really constitute in effect a part of a 55 single inlet port as when oil is fed to any one of said ports, it will be fed to all of said ports. Formed in the plate L are a plurality of ports l which are disposed in a circular series about the center of said

plate and which register with the ports p 65 and the ends of the grooves n, n'; n², n³, n⁴, n⁵ and n⁶. The ports in the plate thus constitute in reality a part of the ports heretofore described, but for the convenience of manufacture, the plates L and M are made 70 separately.

The rotary controlling and distributing member K' is provided with a port or passage k² extending therethrough which, as the member K' is rotated, is adapted to successively align with each of the ports l formed in the plate L so as to connect such ports with the oil receiving chamber at the front of the member K. The front surface of the member K is provided with a plurality of abutments projecting therefrom, k⁴, which are disposed at equal distances around the outer portion thereof, said abutments corresponding in number to the number of outlet tubes which are to be utilized, 80 there being in the present case six such abutments. In the particular embodiment of the invention illustrated, the abutments are provided with a flat upper surface and with an inclined portion leading thereto, although the shape of the abutments may be varied. Tapped onto the front wall of the casing K of the pump opposite the outer portion of the rotary controlling and distributing member K' is a sleeve Q in which 90 is slidably mounted a plunger Q', the inner end of which is adapted to ride over the abutments k⁴ of the member K', when such member is rotated, and the outer end of which is provided with an enlarged head q 100 which works in a hollow nut adjustably secured in the outer end of the sleeve Q. Interposed between the head q of the plunger Q' and an adjustable stop q' which is secured in the end of the hollow nut is a 105 spring q² which tends to move the plunger Q' inwardly into the oil receiving recess or pocket which is formed between the front of the lubricant controlling and distributing member and the front wall of the casing K. 110

The front wall of the casing is provided with a suitable opening which is normally closed by a plug, which opening permits the pump and system to be filled with a lubricant before starting the same. 115

When the pump and system have been filled with lubricant and the lubricant controlling and distributing member K' is rotated, either by reason of the rotation of the engine shaft or when the same is rotated manually, the port k² therein will be, as has heretofore been pointed out, caused to successively register with the ports l which are formed in the plate L and the plunger Q' will be caused to successively ride over the abutments k⁴ of the member K', and will thus be moved into and out of, either partially or wholly, the oil receiving pocket or recess, 120 125

which is provided in the front of the pump casing. The construction is such that whenever the port k^2 of the member K' is moved into alignment with one of the ports L which 5 communicates with one of the inlet ports p, the plunger Q' will be just beginning to rest upon one of the abutments, so that as the port K² passes over such port L, a quantity of lubricant will be drawn into the oil receiving 10 pocket in the front of the casing equal in volume to the space displaced by the plunger as it rides upon the abutment. As the plunger rides upon the abutment, the port k^2 of the member K' will be moved 15 out of alignment with the port l which communicates with one of the inlet ports and into alignment with one of the ports which communicates with one of the passages leading to one of the outlet tubes. As the port k moves into alignment with this port, the 20 plunger rides off of the abutment and is projected by its spring into the oil receiving pocket, thus forcing therefrom and out through said outlet tube a quantity of lubricant 25 equal to the displacement of the plunger. This action will be repeated throughout the rotation of the member K', so that it will be seen that there will be constantly forced through each of the outlet 30 pipes a predetermined amount of lubricant, which will be delivered to the various bearings in the manner heretofore described.

Owing to the fact that all of the outlet pipes except that which leads to the timing 35 gears connect a plurality of bearings serially, it will be seen that each of said bearings is absolutely certain of receiving its proper share of lubricant, particularly in view of the supplemental oil forcing means which is 40 utilized in connection with each of the outlet pipes. This serial lubrication of a plurality of bearings is advantageous not only because it reduces the number of outlet connections which are necessary, but also because 45 where separate outlet pipes are led to the various bearings from a single oil supply, the tendency of the lubricant is to seek the easiest course, so that frequently some of the bearings do not receive any lubricant, 50 while others of the bearings receive too much lubricant.

By adjustably supporting the hollow nut Q² in the sleeve Q it is possible by varying the 55 position of the nut in said sleeve to vary the distance which the plunger will project into the oil receiving pocket and to thus regulate the amount of oil which will be drawn into said pocket and forced out therefrom through the various outlet connections, and 60 as the sleeve and the hollow nut carried thereby are mounted in the front wall of the casing and are hence readily accessible from the driver's seat it will also be seen that any desired adjustment can be quickly

and readily made. To enable the operator 65 to determine the extent of adjustment of the plunger obtained by shifting the nut Q², the adjacent portions of said nut and the sleeve Q are conveniently provided with scale markings. 70

The advantages of a pump of the construction herein described are numerous. It may be mentioned, however, that inasmuch as the pump is very small in size, it may be positioned at any place and at any distance 75 from the oil storage tank, thus enabling the storage tank to be disposed in any convenient part of the machine, when the device is used in connection with automobiles. Furthermore, the construction of the pump is such 80 that it will at all times automatically develop sufficient pressure to force the oil to the proper points under practically all engine conditions, even should the outlet pipe become clogged to a certain extent. The construction is also a highly advantageous one, 85 inasmuch as the amount of lubricant which is forced to the bearings is automatically regulated so that there is no danger of over-lubrication or not enough lubrication, and 90 the many objections due to this cause are overcome.

A further advantage of the herein described construction of pump is that the parts can be quickly and readily adjusted 95 to accurately regulate the amount of oil which is to be forced to the outlet connection.

While a convenient embodiment of the invention is illustrated in the accompanying drawings, it will be understood that many changes may be made to the particular form and construction therein shown without departing from the spirit and scope of the invention as defined in the appended claims. 100

What I claim is:

1. In a lubricating system for engines, the combination with a plurality of bearings to be lubricated, of a main oil forcing means provided with an outlet pipe connected in series with said bearings, and a supplemental oil forcing means for assisting the flow of oil through said bearings. 105

2. In a lubricating system for engines, the combination with the engine shaft of a plurality of bearings to be lubricated, a main oil forcing means provided with an outlet pipe connected in series with said bearings, supplemental means automatically operable upon the rotation of the engine shaft for forcing the oil from said outlet pipe through 110 said bearings. 115

3. In a lubricating system for engines, the combination with the engine shaft of a plurality of bearings to be lubricated, a main oil forcing means automatically operable upon the rotation of said engine shaft provided with an outlet pipe connected in series 125 with said bearings, and supplemental means

- automatically operable upon the rotation of the engine shaft for forcing the oil from said outlet pipe through said bearings.
4. In a lubricating system for engines, the combination with a source of lubricant, of a plurality of bearings, a single connection between the bearings and the source of lubricant, a main controlling element for the lubricant and supplemental elements for assisting said main controlling element located in said connection at different distances from the source.
5. In a lubricating system, the combination with a rotatable shaft, of a source of lubricant, a main oil forcing means, a series of bearings, said main oil forcing means being provided with a connection extending to said bearings and with means automatically operable upon the rotation of the shaft for taking a predetermined amount of oil from the source of lubricant and discharging the same under pressure, through said connection, and centrifugally operated means actuated by said shaft for assisting the main oil forcing means in forcing the oil from said connection through said bearings.
6. In a lubricating system, the combination with a rotatable shaft, of bearings, a source of lubricant, means for forcing oil from said source of lubricant to one of said bearings, and means operated automatically by the rotation of said shaft for transferring the oil under pressure from said last mentioned bearing to another of said bearings.
7. In a lubricating system, the combination with a rotatable shaft, of bearings, a source of lubricant, means for forcing oil from said source of lubricant to one of said bearings, and centrifugally operated means actuated by said shaft for transferring oil under pressure from said last mentioned bearing to another of said bearings.
8. In a lubricating system, the combination with a rotatable shaft, of a plurality of bearings, a source of lubricant, a main oil forcing element connected to the source of lubricant and having a single outlet connection extending to all of said bearings, and a supplemental oil forcing member positioned within one of said bearings for assisting said main oil forcing member in forcing the oil through said bearings.
9. In a lubricating system, the combination with a rotatable shaft, of a plurality of bearings, a source of lubricant, a main oil forcing element connected to the source of lubricant and having a single outlet connection extending to all of said bearings and a pump positioned within one of said bearings and automatically operable when the shaft is rotated to assist the main oil forcing member in forcing oil through said bearings.
10. In a lubricating system, the combina-
- tion with a rotatable shaft, of a plurality of 65 bearings, a source of lubricant, a main oil forcing element connected to the source of lubricant and having a single outlet connection extending to all of said bearings and a centrifugal actuated pump positioned within 70 one of said bearings and automatically operable when the shaft is rotated to assist the main oil forcing member in forcing oil through said bearings.
11. In a lubricating system, the combination with a rotatable shaft, of a plurality of 75 groups of bearings, a source of lubricant, a main pump separate from said source of lubricant, said main pump being provided with an inlet port connected to said source 80 of lubricant, with a plurality of outlet connections, each of which is connected in series with all of the bearings of one of said groups, and with lubricant controlling and distributing means for successively delivering 85 oil under pressure to said oil connections.
12. In a lubricating system, the combination with a rotatable shaft, of a plurality of 90 groups of bearings, a source of lubricant, a main pump separate from said source of lubricant, said main pump being provided with an inlet port connected to said source 95 of lubricant, with a plurality of outlet connections, each of which is connected in series with all of the bearings of one of said groups, and with lubricant controlling and distributing means for successively delivering oil under pressure to said outlet connections.
13. In a lubricating system for engines, the combination with the engine shaft, provided with a plurality of cranks, a plurality 105 of bearings for said shaft, the engine cylinders, pistons therein, pitmen connecting said pistons and the cranks of the engine shaft, a source of lubricant, a main oil forcing pump connected to said source of lubricant and provided with a plurality of outlet connections each of which connects serially one of the engine shaft bearings, one of the crank pin bearings, and one of the piston pin bearings, said main oil pump being provided 110 with lubricant controlling and distributing means for successively delivering oil under 115 pressure to said outlet connections.
14. In a lubricating system for engines, the combination with the engine shaft, provided with a plurality of cranks, a plurality 120 of bearings for said shaft, the engine cylinder, pistons therein, pitmen connecting said pistons and the cranks of the engine shaft, a source of lubricant, a main oil forcing pump connected to said source of lubricant and provided with a plurality of outlet connections each of which connects serially one of 125

the engine shaft bearings, one of the crank pin bearings, and one of the piston pin bearings, said main oil pump being provided with lubricant controlling and distributing means for successively delivering oil under pressure to said outlet connections, and supplemental oil forcing means associated with each of said outlet connections.

15. In a lubricating system for engines, the combination with the engine shaft, provided with a plurality of cranks, a plurality of bearings for said shaft, the engine cylinder, pistons therein, pitmen connecting said pistons and the cranks of the engine shaft, a source of lubricant, a main oil forcing pump connected to said source of lubricant and provided with a plurality of outlet connections each of which connects serially one of the engine shaft bearings, one of the crank pin bearings and one of the piston pin bearings, said main oil pump being provided with lubricant controlling and distributing means for successively delivering oil under pressure to said outlet connections, and a centrifugally operated oil pump actuated by the rotation of the engine shaft associated with each of said outlet connections.

16. In a lubricating system for engines, the combination with the engine shaft provided with a plurality of cranks, a plurality of bearings for said shaft, the engine cylinders, pistons therein, pitmen connecting said pistons and the cranks of the engine shaft, a cam shaft, bearings therefor, timing gears connecting the cam and engine shaft, a source of lubricant, a main oil forcing pump connected to said source of lubricant and provided with a plurality of outlet connections each of which connects serially with one of the engine shaft bearings, one of the crank pin bearings, and one of the piston bearings, and with a sight feed and an outlet connection extending therefrom to the timing gears connecting the engine and cam shafts, said pump being provided with lubricant controlling and distributing means for successively delivering oil under pressure to said outlet connections.

17. In a lubricating system for engines, the combination with the engine shaft provided with a plurality of cranks, a plurality of bearings for said shaft, the engine cylinder, pistons therein, pitmen connecting said pistons and the cranks of the engine shaft, a cam shaft, bearings therefor, timing gears connecting the cam and engine shaft, a source of lubricant, a main oil forcing pump connected to said source of lubricant and provided with a plurality of outlet connections each of which connects serially with one of the engine shaft bearings, one of the crank pin bearings, and one of the pistons, and with a sight feed and an outlet connection extending therefrom to the timing gears

connecting the engine and cam shafts, said pump being provided with lubricant controlling and distributing means for successively delivering oil under pressure to said outlet connections, and supplemental oil forcing means associated with each of the outlet connections which connects serially the engine shaft bearings, crank pin bearings, and piston pin bearings.

18. A lubricating system for engines having parts to be lubricated, comprising a casing, a member rotatably supported therein, said casing being provided with an oil inlet and with a plurality of oil outlets, said rotatable member and an adjacent portion of the casing being fashioned to provide a lubricant receiving pocket therebetween adapted upon rotation of the rotatable member to be placed in communication alternately with said inlet and said outlets, the outlets being connected to said pocket successively, said casing being provided with a spring pressed plunger normally projecting within the pocket, and said rotatable member being provided with a plurality of separated abutments positioned to successively engage said plunger and move the same outwardly upon rotation of said rotatable member.

19. In a lubricating system for engines having parts to be lubricated, the combination of a casing, a member rotatably supported therein, said member and said casing being fashioned to provide an oil receiving pocket therebetween, said casing being provided with an equal number of alternately arranged inlet and outlet ports leading thereinto and said rotatable member being provided with a port therein extending from said pocket adapted to successively communicate with said inlet and outlet ports upon rotation of the rotatable member, a single oil supply pipe connected to all of said inlet ports, an outlet pipe connected to each of said outlet ports, and means for drawing a predetermined amount of oil into said pocket when the port in the rotatable member is in communication with each of the inlet ports and for forcing a like amount therefrom when said port is in alignment with each of the outlet ports.

20. In a lubricating system for engines having parts to be lubricated, a distributor, the same comprising a casing, a member rotatably supported therein, said member and said casing being fashioned to provide an oil receiving pocket therebetween, said casing being provided with an equal number of alternately arranged inlet and outlet ports leading thereinto and said rotatable member being provided with a port therein extending from said pocket adapted to successively communicate with said inlet and outlet ports upon rotation of the rotatable

- member, a single oil supply pipe connected to all of said inlet ports, an outlet pipe connected to each of said outlet ports, and a displacement member movable out of said 5 oil receiving pocket when the port in the rotatable member communicates with any one of the inlet ports and into the pocket when said port communicates with any one of said outlet ports.
- 10 21. In a lubricating system for engines having parts to be lubricated, a distributer, the same comprising a casing, a member rotatably supported therein, said member and said casing being fashioned to provide an 15 oil receiving pocket therebetween, said casing being provided with an equal number of alternately arranged inlet and outlet ports leading thereinto and said rotatable member being provided with a port therein extending 20 from said pocket adapted to successively communicate with said inlet and outlet ports upon rotation of the rotatable member, a single oil supply pipe connected to all of said inlet ports, an outlet pipe connected 25 to each of said outlet ports, and said casing and rotatable member being provided one with a plunger normally projecting within the pocket and the other with a series of separated abutments corresponding 30 in number to the number of inlet ports and positioned to successively engage said plunger upon rotation of said rotatable member to move the same out of the pocket when the pocket is in communication with 35 any one of the inlet ports, said abutments being of a size to move out of engagement with the plunger when the pocket is in communication with the respective outlet ports.
22. In a lubricating system for engines having 40 parts to be lubricated, a distributer, the same comprising a casing, a member rotatably supported therein, said member and said casing being fashioned to provide an oil receiving pocket therebetween, said casing being provided with an equal number of alternately arranged inlet and outlet ports leading thereinto, and said rotatable member being provided with a port therein extending 45 from said pocket adapted to successively communicate with said inlet and outlet ports upon rotation of the rotatable member, a single oil supply pipe connected to all of said inlet ports, an outlet pipe connected 50 to each of said outlet ports, and said casing being provided with a spring pressed plunger normally projecting within the pocket and said rotatable member being provided with a series of separated abutments corresponding 55 in number to the number of inlet ports and positioned to successively engage said plunger upon rotation of said rotatable member to move the same out of the pocket when the pocket is in communication with 60 any one of the inlet ports, said abutments

being of a size to move out of engagement 65 with the plunger when the pocket is in communication with the respective outlet ports.

23. In a lubricating system for engines having parts to be lubricated, a distributer, the same comprising a casing, a member rotatably supported therein, said member and casing being fashioned to provide an oil receiving pocket therebetween, said casing being provided with an equal number of alternately arranged inlet and outlet ports and 70 said rotatable member being provided with a port therein extending from said pocket adapted to successively communicate with each of said inlet and outlet ports upon rotation of said rotatable member, a sight 75 feed on the casing connected to one of said outlet ports, an outlet pipe directly connected to each of the other outlet ports, an oil inlet pipe in communication with all of said inlet ports, and means for drawing a 80 predetermined amount of oil into the pocket when the same is in communication with each of the inlet ports and for forcing a like amount therefrom when said pocket is 85 in communication with each of the outlet 90 ports.

24. A lubricating system for engines having parts to be lubricated comprising a distributer, the latter including a cylindrical casing, a cylinder rotatably supported therein, said cylinder and casing being fashioned to provide an oil receiving pocket therebetween, the adjacent end faces of said cylinder and said casing being provided with 95 ports therein adapted to alternately connect 100 upon rotation of the cylinder a single inlet pipe and a series of outlet pipes with said pocket, said inlet pipe and said plurality of outlet pipes, and a displacement member automatically movable into said pocket 105 when the same is connected to each of the outlet pipes.

25. A lubricating system for engines having parts to be lubricated comprising a distributer, the latter including a cylindrical casing, a cylinder rotatably supported therein, said cylinder and said casing being fashioned to provide an oil receiving pocket, one 110 end wall of said casing being provided with an equal number of oil inlet and oil outlet 115 ports therein, said inlet and outlet ports being alternately disposed in a circular path about the axis of the cylinder, said cylinder being provided with a passage extending 120 from the pocket to the end wall thereof and positioned to successively register with the ports in the end wall of the casing upon rotation of the cylinder, and a displacement member automatically movable out of said 125 pocket when the port in the cylinder registers with each of said inlet ports and into said pocket when the passage in the cylinder registers with each of said outlet ports.

26. In a lubricating system for engines, a distributor comprising a cylindrical casing, a cylinder rotatably supported therein, said cylinder and said casing being fashioned to provide an oil receiving pocket, one end wall of said casing being provided with an equal number of oil inlet and oil outlet ports therein, said inlet and outlet ports being alternately disposed in a circular path about the axis of the cylinder, a single oil inlet pipe connected to all of said inlet ports, an oil outlet pipe connected to each of said outlet ports, said cylinder being provided with a passage extending from the pocket to the end wall thereof and positioned to successively register with the ports in the end wall or the casing upon rotation of the cylinder, and a displacement member automatically movable out of said pocket when the port in the cylinder registers with each of said inlet ports and into said pocket when the passage in the cylinder registers with each of said outlet ports.
27. In a lubricating system for engines, a distributor comprising a cylindrical casing, a cylinder rotatably supported therein, said cylinder and said casing being fashioned to provide an oil receiving pocket, one end wall of said casing being provided with an equal number of oil inlet and oil outlet ports therein, said inlet and outlet ports being alternately disposed in a circular path about the axis of the cylinder, a single oil inlet pipe connected to all of said inlet ports, a sight feed upon the exterior of the casing connected to one of said outlet ports, an oil outlet pipe directly connected to each of the other of said outlet ports, said cylinder being provided with a passage extending from the pocket to the end wall thereof and positioned to successively register with the ports in the end wall of the casing upon rotation of the cylinder, and a displacement member automatically movable out of said pocket when the port in the cylinder registers with each of said inlet ports and into said pocket when the passage in the cylinder registers with each of said outlet ports.
28. In a lubricating system for engines, a distributor comprising a cylindrical casing, a cylinder rotatably supported therein and provided with a shaft extending therefrom, said cylinder and casing being fashioned to provide an oil pocket therebetween, one end wall of said casing being provided with an equal number of oil inlet and oil outlet ports therein, said inlet and outlet ports being alternately disposed and positioned at points equi-distant from the axis of the cylinder, said cylinder being provided with a passage extending from the pocket to an end wall thereof and positioned to successively register with the ports in the end wall of the casing upon rotation of said cylinder, means for yieldably holding the ported end 65 walls of the casing and cylinder in yieldable engagement with each other, and a displacement member automatically movable out of said pocket when the port in the cylinder registers with each of said inlet 70 ports and into said pocket when the passage in the cylinder registers with each of said outlet ports.
29. In a lubricating system for engines having parts to be lubricated, a distributor, 75 comprising a casing provided with an oil inlet leading thereto and an oil outlet leading therefrom, a rotatable member positioned in said casing, said rotatable member and casing being fashioned to provide 80 an oil pocket or chamber therebetween, and said rotatable member being provided with a passage adapted upon rotation thereof to successively connect said pocket with said inlet and outlet, and a displacement member 85 movable out of said pocket when the same is placed in communication with the inlet and into said pocket when the same is placed in communication with said outlet, said rotatable member being provided with 90 means for directly engaging said displacement member to shift the same in at least one direction.
30. In a lubricating system for engines having parts to be lubricated, a distributor, 95 comprising a casing provided with an oil inlet leading thereto and an oil outlet leading therefrom, a rotatable member positioned in said casing, said rotatable member and casing being fashioned to provide an 100 oil receiving pocket therebetween adapted upon rotation of said rotatable member to be placed alternately in communication with said oil inlet and outlet, a displacement member movable into and out of said pocket, 105 and means for varying the extent of movement of said displacement member.
31. In a lubricating system for engines having parts to be lubricated, a distributor, 110 comprising a casing provided with an oil inlet leading thereto and an oil outlet leading therefrom, a rotatable member positioned in said casing, said rotatable member and casing being fashioned to provide an oil receiving pocket therebetween adapted 115 upon rotation of said rotatable member to be placed alternately in communication with said oil inlet and outlet, said rotatable member and casing being provided one with a plunger normally extending into the pocket and the other with an abutment for shifting said plunger upon rotation of the rotatable member, and means for adjusting the plunger to vary the extent to which it projects into the pocket.
32. In a lubricating system for engines having parts to be lubricated, a distributor, 120 comprising a casing provided with an oil

inlet leading thereinto and an oil outlet leading therefrom, a rotatable member positioned in said casing, said rotatable member and casing being fashioned to provide an oil receiving pocket therebetween adapted upon rotation of said rotatable member to be placed alternately in communication with said oil inlet and outlet, said casing being provided in the outer wall thereof 10 with an adjustable hollow sleeve, a spring

pressed plunger mounted in said sleeve and projecting into said pocket, and said rotatable member being provided with an abutment positioned to engage said plunger.

In testimony whereof I affix my signature 15 in presence of two witnesses.

OSCAR ROBERT GRÖNKWIST.
